UNITED STATES PATENT OFFICE.

PIERRE BONNIER, OF PARIS, FRANCE.

PROCESS OF COLOR-PRINTING.

1,108,063.

Specification of Letters Patent. Patented Aug. 18, 1914.

Application filed July 5, 1911. Serial No. 636,901.

To all whom it may concern:

Be it known that I, PIERRE BONNIER, doctor of medicine, citizen of the French Republic, residing at Paris, Department of Seine, France, have invented certain new and useful Improvements in Processes for Color-Printing, of which the following is a specification.

This invention relates to a process of speedy color printing which is mainly appropriated to the color printing of daily papers and which is of the kind of processes in which cylinders are interposed between the inking rollers and the printing cylinder. It has for its object to remedy the disadvantages of the hitherto known processes and mainly the necessity of manufacturing many printing devices and to avoid the difficulties in the starting of the printing machine and in obtaining the accordance between the cylinders.

The invention consists in using as auxiliary cylinders to be interposed between the inking rollers and the printing cylinder, auxiliary cylinders having a coating of gelatin, india rubber or any suitable material which is able to take up and to give again the ink; the said auxiliary cylinders, with their coating, having the same diameter as that of the printing cylinder, and each of said auxiliary cylinders corresponding to one of the colors which are to be simultaneously printed with the printing cylinder.

The invention consists further in using the printing cylinder, which carries all the types or the like forming the whole of the composition to be printed, to print first on the coating of the auxiliary cylinders the whole of the said composition; in taking away by chemical means or with a tool or by any other suitable means, a suitable depth of the coating of each one of the said auxiliary cylinders in the parts corresponding to the parts of the composition which are not to be printed with the color to which the auxiliary cylinder corresponds, in order that the ink be taken up by the auxiliary cylinder in the parts only which correspond to the parts of the composition which is to be printed with the color corresponding to the said auxiliary cylinder. The said auxiliary cylinders are mounted in the printing machine adjacent to the printing cylinder to circumferentially engage the latter, and when the machine is started each auxiliary cylinder will take up the ink, having a de-

termined color, only in the parts of its coating which have been left for the taking up of the ink, and give it again to the printing cylinder at the corresponding parts; and the printing cylinder will immediately print on the paper or the like the composition, which it carries, in as many colors as there are auxiliary cylinders.

Such a process is very easy and very speedy; furthermore it allows a set of auxiliary cylinders to be prepared in advance for the immediate change of an auxiliary cylinder if it is worn out before the end of the printing. And in order that the invention may be more fully understood, it will be more completely described hereinafter with reference to the accompanying drawing which shows diagrammatically a printing machine which is disposed for printing simultaneously in two colors, for instance in black and in red.

In the drawing, *a* is the printing cylinder; *b* a plate on which is the paper or the like *c* to be printed; *d* are the inking rollers for the black color and *d'* the inking rollers for the red color; *e* is the auxiliary cylinder for the black color and *e'* the auxiliary cylinder for the red color.

The auxiliary cylinders have a coating of gelatin, india rubber or any suitable material which is able to take up and to give again the ink; and the said auxiliary cylinders have with their coating the same diameter as that of the printing cylinder.

Means, not shown on the drawing, oblige the auxiliary cylinders to be rotated at the same speed as the printing cylinder.

The working is as follows: The printing cylinder *a* having been provided in any known manner with the whole of the composition which is to be printed, the machine is set into rotation, and the printing cylinder *a* prints on the coating of the auxiliary cylinders *e*, *e'* the whole of the said composition. The said auxiliary cylinders are then taken away from the machine and, by chemical means, with a tool or by any suitable means, a suitable depth of the coating of the auxiliary cylinder *e* is taken away in the parts *f* corresponding to the parts of the composition which are not to be printed in black, in order that the said auxiliary cylinder *e* takes up the black color only with the parts *g* of its coating corresponding to the parts of the composition which are to be printed in black. In the same manner a

suitable depth of the coating of the auxiliary cylinder e' is taken away in the parts f' corresponding to the parts of the composition which are not to be printed in red, 5 in order that the said auxiliary cylinder e' takes up the red color only with the parts g' of its coating corresponding to the parts of the composition which are to be printed in red. The auxiliary cylinders e e' , thus 10 prepared, are mounted again in the machine in such a manner that the composition printed on the said auxiliary cylinders be in accordance with the composition on the printing cylinder; this being, in fact, very 15 easy with suitable marks. The machine is then ready for printing.

When the machine has been started, the parts g of the auxiliary cylinder e take up the black color from the inking rollers d 20 and give it again to the corresponding parts h of the printing cylinder a ; and the parts g' of the auxiliary cylinder e' take up the red color from the inking rollers d' and give it again to the corresponding parts h' 25 of the printing cylinder. The printing cylinder prints directly on the paper or the like e the whole of the composition and the parts h of the said composition are printed in black, while the parts h' are printed in 30 red.

It is obvious that the invention is not in

any way limited to the manner of realization of the process hereinbefore described and that it comprises all possible variations.

Having now particularly described and ascertained the nature of the said invention, and in what manner the same is to be performed I declare that what I claim is—

The process of color printing consisting in removably disposing auxiliary cylinders 40 between the main cylinder and inking rollers of a printing press and directly printing by the main cylinder all the composition to be printed on the auxiliary cylinders, dismounting and removing the auxiliary cylinders and removing parts of the composition printed thereon from the main cylinder that are not to be printed with any particular color of ink that may be used with the auxiliary cylinders, and then remounting the auxiliary cylinders between the main cylinder and inking rollers to carry the ink from the said rollers to the main cylinder in accordance with the remaining printing portions of said auxiliary cylinders. 45

In testimony whereof I have hereunto set my hand in presence of two subscribing witnesses.

PIERRE BONNIER.
